RASMUS M. FRANDSEN, OF BURLINGAME, CALIFORNIA

STRUCTURAL-STEEL TRUSS JOIST

Application filed December 16, 1927. Serial No. 240,421.

The present invention relates to improvements in structural steel truss-joist constructions, and has for its primary object the provision of a structural steel joist consisting of several series of varying lengths, depths, load capacities, etc., all to be fabricated of commercially obtainable structural shapes, angles, T's and flats connected by electric spot-welding processes and designed 10 to carry floors in steel constructions, the trusses being designed in accordance with the latest specifications for structural steel buildings as formulated and recommended by the American Institute of Steel Construction.

Another object of my invention is the provision of a fabricated steel truss or joist which is adapted to be placed upon spaced supporting beams of steel structures to span 20 the intervening space, with ends so thus supported as to allow for expansion and contraction of the structure.

An additional and most important object of the invention is the provision of a fabricated truss or joist constituted of comparatively light-weight material spot-welded together in such manner as to cause the various elements thus joined to be fused together substantially as a rigid unit.

In the accompanying drawings, forming a part of this specification, and, in which, similar characters of reference refer to like parts, throughout:

Figure 1—1A is a side elevation of a truss or joist constructed in accordance with the principles of my invention, showing one end thereof resting upon an I-beam of a building structure, a fragmentary portion of which is shown;

Figure 2—2A is a top plan view of the joist shown in Figure 1—1A;

Figure 3 is an end view, showing the relative arrangement of the various parts constituting the truss or joist;

Figure 4 is a vertical sectional view taken through the upper and lower chord members of the truss or joist, showing the diagonals and compression web members thereof, the section being taken on the line 4—4 of Figure 1;

Figure 5 is a fragmentary side elevation, showing a slightly modified form of joist for supporting increased weights in heavier structures;

Figure 6 is a plan detail of one of the 55 T-shaped compression web members of the truss or joist;

Figure 7 is a side elevation thereof;

Figure 8 is an end view of the members shown in Figures 6 and 7;

Figure 9 is a plan view of one of the screed clips used in connection with my improved truss or joist;

Figure 10 is a sectional detail taken through the upper chord of the truss or 65 joist, showing the manner in which the screed clips are secured in place between the angle bars comprising the upper chord of the joist;

Figure 11 is an end view of the screed 70 clip shown in Figures 10 and 11;

Figure 12 is a top plan view of a slightly modified form of screed clip for use in retaining transversely arranged stringers;

Figure 13 is an elevation of the clip shown 75 in Figure 12;

Figure 14 is a sectional detail taken through the upper chord of the truss and showing the clip supported in place between the angle bars of the upper chord of the 80 truss, as in Figure 10;

Figure 15 is an elevation of a furring staple used in connection with my truss or joist to hold the metal lath in position;

Figure 16 is an edge view thereof; and 85

Figure 17 is a sectional detail of the clip used in connection with the lower chord angle bars for holding the furring channel straps in position, the section being indicated by the line 17—17 in Figure 1. 90

In designing the trusses a uniform floor load of 40 lbs. per square foot of live load and 50 lbs. per square foot of dead load is assumed, and a spacing of 2 feet center to center of the trusses. Each truss is designed for its maximum span and its maximum shears. As the shears are inversely proportional to the spans, the shear loads are inversely proportional to the spacings. The trusses are also designed to care for 100

web shears caused by applying live loads over only part of the span. Double diagonals, or counter braces, are introduced where partly uniformly distributed loads will change tensional stresses in diagonals to compression. In determining those panels which will require counter braces to prevent reversal of stress in the diagonals an occasional live load is assumed at each panel point equal to three times the dead load. The top chord members are designed to carry in addition to the direct compression a bending moment imposed from the slab above between each panel point. The bottom chord members are designed to take the tensional stresses plus the bending moment due to ceiling loads applied at center points between panel points.

The invention resides in the method of arranging commercially obtainable small structural shapes in such manner as will most economically take care of the imposed loads under all assumed conditions, and connecting together these members by an electrical "spot-welding" fusing of them through and through, practices, to my knowledge, never before attempted, either in the assemblage of material or in the joining of these together. Electric welding in this construction has been found to be perfectly feasible, only necessitating the building of specially constructed electric welding machines, and much more economical than the welding accomplished with the arc-welding process.

It is realized that there are other types of steel joists, but these are either of I-beam character or formed of round bars, the same as are used in concrete reinforcing. The bar types are products of the arc-welding process and are possessed of but little lateral stiffness. In these the neutral axes of the chord members are practically at the center line of these bars, while in my system the neutral axes are nearer the extremities of the chord members, this, therefore, being more economical in requirement of metal to meet the stresses. The long leg of the top chord angles, always horizontal, gives also more lateral stiffness than that of any other system thus far introduced. Additionally my compression web members are all of T-shape and vertical arrangement, making for increased stiffness and greater economy over those of bar type, while the tensional web members are all of flats, meeting all requirements, since these are not designed to carry compression stresses, and greatly reducing weight of material.

The variation of stresses in the end members resulting from the variation of span of supports has also been taken care of in a novel manner by the combination of principles for angle and plate girders, the cantilever beam, and the modified Pratt truss.

For the sake of practicability and simple

and easy fabrication, the bottom chord angles are all bent to the same slope for all trusses, an 8" to 12" slope. Thus one specially set "bulldozer" can be made to deform all angles for all trusses.

To insure perfect "spot-welding" results, it is absolutely required that all steel must be cleaned of rust and scale by the pickling process to insure perfect contact of metal, and that the truss members be assembled in a rack, carried by a rolling table, clamped in place thereon, and moved to a stationary electric welding machine for welding. After welding, they are submitted to rigid tests, painted by subjecting them to the dipping process, and hereafter thoroughly dried preliminary to shipping.

Referring with greater particularity to the drawings, the numeral 20 designates the truss or joist as a whole, which joist consists of an upper chord member 21 and a lower chord member 22, both chord members consisting of longitudinally positioned pairs of angle bars 23 and 24 and 23' and 24' arranged back to back and in close proximity to each other, providing interstices 25 and 25' therebetween extending throughout their length, as clearly shown in Figures 2, 3 and 4.

A plurality of vertically disposed compression members 26 are arranged at equal intervals between the chord members and have their extremities 27 entering the interstices 25 and 25' formed between the angle bars, said compression members consisting of T-shaped bars having notched ends providing the members 27, as shown in Figures 6, 7 and 8.

Between each compression member one or more diagonals 28 are arranged and extend from the upper chord member to the lower chord member, with their extremities fitting into the interstices 25 and 25' of the chord members and abutting against the upper and lower-ends, respectively, of successive compression members, as shown in Figure 1, these tending to act as tensioning members, as hereinbefore described. These diagonals consist of flat bars, as shown in cross section in Figure 4, and are varied in cross sectional area, as are the angle bars 23 and 24 and compression members 26, to suit varying conditions, in accordance with the size of the structure.

The angle bars 23' and 24' forming the lower chord member are bent upwardly to form angularly disposed extensions 29, Figure 1, which in turn are bent to form the ends 30, which ends 30 extend parallel with the upper chord member for a distance and terminate flush with the outer ends thereof. The ends 30 of the angle bars 23, 24 and 23' and 24' having interposed therebetween web plates 31, which plates extend from the outer ends of both upper and lower chords to the first compression member 26, as shown in Figure 1.

The ends 30 of the lower chord member of the joist are adapted to rest upon the I-beam supports 32 of the structure, and the lower angle bars 23' or 24' are adapted for clamping to the I-beams by means of C-shaped clamps 32', which clamps prevent vertical movement of the joist ends relative to the supporting beams but allow of longitudinal movement due to expansion and contraction of the parts constituting the joist. Only one end of the truss or joist has been shown and one supporting beam but it is of course to be understood that the opposite end of the truss (not shown) is an exact duplicate of that illustrated in Figure 1 and rests upon a like supporting beam of the building structure.

In structures where it is desired to finish the interior with a plaster or like finish the truss or joist is provided with furring channel supports 33, which supports consist of L-shaped straps having their upper ends bent to form U-shaped retaining members 34, Figures 1 and 3, adapted to hook over the upper angle bars 23 and 24 of the upper chord member and to depend therefrom with their right angle extensions 35 aligned with the lower chord member angle bar 24' and to which angle bar they are secured by means of clips 26, Figures 1 and 17.

The upright members 37 of the supports 33 are provided with furring channels 38 and the extensions 35 carry furring channels 39 to which the metal lath 40 and plaster 41 are secured, as shown in Figure 1.

As hereinbefore described, the various elements constituting the truss or joist are assembled and the web members 31 are securely welded and united to the angle bars 23 and 24 and 23' and 24' forming respectively, the upper and lower chords, at a series of electrically welded points 42 and 43 and the upper and lower extremities of the compression members are electrically welded to said bars at the points 44 as are also the diagonals at the points 45. The fusing of the various parts constituting the truss or joist at the points indicated cause their securement together as a rigid unit, as described, this welding process consists of a complete fusing of the various parts at the points indicated, which welding process tends to actually unite these parts. In the use of a mere surface weld, such as that obtained through the so called spot welding process, the parts would not be sufficiently united to produce a rigid structure calculated to withstand strains and stresses to which the joist may be subjected in actual practice.

In Figures 1A and 2A, I have illustrated the preferred method of anchoring the reinforcing material to the joists, and, in this construction, such reinforcing material consists of laying expanded metal 46, across the joists, which material is provided with ribs

47 adapted to be embraced by special staples 48, Figures 1A, 2A and 15, having shanks 49 adapted to fit into the interstices 25 of the joist and to be driven home to securely hold the reinforcing material in place. Special screed clips 50 are also provided for use in connection with my improved truss or joist and comprise stringer retaining members 51 and shanks 52 adapted for wedging into the interstices 25 in a similar manner to that of the staples 48. These screed clips receive the stringers 52 and the retaining members 51 thereof hold the stringers in spaced relation above the reinforcing material, as shown in either the wood floor construction, the concrete floor construction, or the tile finish.

It will be observed with reference to Figure 5 that I have shown a slightly modified form of joist construction, such form being utilized in large structures and comprising upper and lower chord members 53 and 54, compression bars 55, and diagonals 56. The material used in this form is somewhat heavier than that used in the other forms shown, the various elements being considerably heavier and the lower chord 54 extending upwardly and angularly and abutting against an auxiliary chord member 57 which is electrically welded to the web 58 at the points 59, with the lower chord extension 60, welded at the points 61 to said web plate 58.

In the present improved truss and floor construction, special provisions are made for floor support, when constructed on expanded metal, through the employment of a special galvanized iron staple, such as is shown in Figures 15 and 16, this being of a thickness somewhat greater than the slightly spaced interstices between the backs of the top chord angles. The staple when placed over the expanded metal and as close as possible to the panel points is driven securely home, thus serving to secure the expanded metal in position and prevent its movement either laterally or longitudinally.

Obviously, my construction of trusses permits the use of much lighter materials for the support of a given weight than would be required under present constructions, there being here no loss of material through punching for bolts with attendant weakening and lack of rigidity of structure.

Having thus described my invention, I claim, and desire to secure by Letters Patent:

In a truss or joist of the class described, embodying a plurality of fabricated members electrically welded together as a unit, said members comprising upper and lower chord members each consisting of a pair of angle bars arranged in close proximity and of opposite disposition, vertically disposed compression members extending between said chord members and having their extremities interposed between the angle bars comprising each pair, diagonals comprising flat ten-

sion bars extending diagonally between the compression members and terminating in abutted relation with the upper and lower ends, respectively, of successive compression bars, the lower chord bars from the point of connection with the endmost compression member being inclined upward toward the upper chord bars and then extending parallel therewith above the longitudinal axis of the truss, providing a supporting end for the joist, and a web plate lying between the backs of the angle bars forming the end portions of the chord bars, the inner end of the upper edge of said web plate terminating short of the point of connection of the upper end of the endmost compression member with the upper chord, and the lower edge of said plate extending a short distance down the inclined portion of the lower chord and then inclined upwardly and terminating near the point of termination of the inner end of the upper edge of said web plate, the welded connection of the upper and lower edges of the web being confined respectively to the upper horizontal member, the lower horizontal member and a portion of the upper end of the inclined portion of the lower chord of the supporting end of the joist.

In testimony whereof, I have hereunto affixed my signature this 23rd day of November, 1927.

RASMUS M. FRANDSEN.
